UNITED STATES PATENT OFFICE.

WILLIAM NORTON, OF SAN FRANCISCO, CALIFORNIA.

ANTISKIDDING DEVICE.

1,183,107.

Specification of Letters Patent.

Patented May 16, 1916.

Application filed August 21, 1915. Serial No. 47,541.

To all whom it may concern:

Be it known that I, WILLIAM NORTON, a citizen of the United States, residing in the city and county of San Francisco and State of California, have invented a new and useful Improvement in an Antiskidding Device, of which the following is a specification.

My invention relates particularly to improvements in the construction of the antiskidding device for which Letters Patent of the United States numbered 1,147,040 were issued to me on the 20th day of July, 1915; and has for its objects: First, to provide an improved antiskidding device so mounted upon the frame of a motor vehicle or the like that shocks and vibrations received by the device will be prevented from reaching the frame or chassis of the vehicle. Second, to provide an improved device of the character described having resilient shock absorbing means interposed between the contact shoe and the operating means therefor. Third, to provide an improved device that shall be simple, effective, cheap and durable in construction and in operation. Fourth, to provide an improved device of the character described that shall be inconspicuous when in an inoperative position so as not to mar or detract from the appearance of the car or vehicle. I accomplish these several features by means of the device disclosed in the drawings forming a part of the present specifications wherein like characters of reference are used to designate similar parts throughout the said specifications and drawings and in which—

Figure 1 is a broken side elevation of a car or vehicle with the body and nigh rear wheel removed in order to disclose the manner in which the improved device is attached thereto, the dotted lines indicating the inoperative, and the full lines indicating the operative positions, respectively. Fig. 2 is a transverse sectional view taken on line X—X of Fig. 1 of the drawings in the direction indicated.

Referring to the drawings the numeral 1 is used to designate a vertically disposed tubular member pivotally mounted, by means of trunnions 2, between longitudinal channels 3 of a frame or chassis 4. The member 1 is also provided with longitudinal slots 5 and lateral lugs 6 on the lower end thereof to which lugs 6 are secured lateral inclined braces 7, said braces 7 being secured at their upper ends to the trunnions 2 but

on the opposite sides of the channels 3, thereby providing a suitable support against lateral movement.

What I term a sleeve 8, to differentiate from the tubular member 1, is slidably mounted within said tubular member 1 and is provided with lateral lugs 9 which project through and beyond the slots 5 of said member 1. The upper end of the sleeve 8 is closed as at 11 while the lower end thereof is provided with an annular flange 12 adapted to engage and raise a plunger or piston 14 secured to a stem 16 of a longitudinally disposed shoe 17, having longitudinal grooves 18 in the bottom thereof. A suitable spring 19 is interposed between the top of the plunger or piston 14 and the closed top 11 of the sleeve 8, the purpose of which will hereinafter more fully appear. A bell crank lever 21 is pivotally mounted upon a bracket 22 rigidly secured to the chassis or frame 4 and is provided with a bifurcated arm 23 which is operatively connected to the lugs 9 of the sleeve 8 by means of connecting links 24, while the other arm 26 of the bell crank lever 21 is operatively connected, by means of a suitable connecting rod 27, to the lower end of an operating lever 28 pivotally mounted upon a sector 29 secured to the chassis or frame 4. The lever 28 is provided with the usual detent 31 and releasing latch 32. The forward end of the shoe 17 is connected to the forward part of a machine by means of a suitable rod 33 which is secured to a somewhat flexible metallic bracket 36.

The operation is as follows: When inoperative the device will be positioned as disclosed in dotted lines in Fig. 1 of the drawings. When the vehicle starts to skid or move sidewise the rear wheels 34 will not follow the front wheels 35. To prevent a side movement of the rear wheels and rear portion of the car or vehicle the lever 28 is moved to the position indicated in full lines in Fig. 1 of the drawings which action will cause the bifurcated arm 23 of the bell crank lever 21 to move the sleeve 8 and shoe 17 slidably mounted therein downward and the latter into contact with a roadway. After the shoe has formed such contact an additional pressure is brought to bear on the lever 28 until the spring 19 is compressed between the top of the piston 14 and the closed top 11 of the sleeve 8. The detent 31 will normally prevent a release or return of

the lever 28 and consequently the shoe 17 will be held in contact with the roadway thereby causing the grooves 18 to engage said roadway and thereby prevent a lateral or skidding movement of the vehicle. While in this position the pressure will be upward through the stem 16 of the piston 14 and onto the spring 19 thereby further compressing said spring. Were the spring 19 not interposed between the piston 14 and the top 11 of the sleeve 8 it is obvious that jars and shocks occasioned by the moving contact of the shoe 17 with the roadway would be communicated directly to the bracket 22 and thereby to the frame or chassis 4 and also to the operating lever 28 which might injure the arm of the operator were he holding said brake or lever 28. These jars and shocks are, however, absorbed by the spring 19 and thereby prevented from reaching the frame 4 of the operating lever 28, which might otherwise injure and wrack said frame 4 and some of the mechanism attached thereto; loosening joints and otherwise damaging the car.

While the device is in an operative position as above described the shoe 17 and tubular member 1 are prevented from moving backward by means of the rod 32 which connects the front end of said shoe 17 with the bracket 36 near the front of the frame 4. The tubular member 1 and shoe 17 slidably mounted therein are also supported against lateral movement, due to the skidding movement, by means of the lateral or side braces 7. Any vibration of a violent nature due to the contact of the shoe 17 with the roadway will be readily taken up by means of the connecting links 24 and also by means of the flexibility of the bracket 36.

It is obvious from the foregoing that I have provided an improved antiskidding device that is adapted to prevent skidding and also means whereby the shocks and jars caused by such skidding will be absorbed before reaching the frame and the operating lever 28.

I am aware that the present state of the art discloses anti-skidding devices comprising a vertically reciprocating member adapted to engage a roadway and thereby retard a forward or lateral movement of a vehicle to which they are attached. I therefore do not wish to claim such a combination broadly but

What I do claim as new and desire to secure by Letters Patent is—

1. An antiskidding device for motor vehicles and the like comprising a vertically disposed tubular member pivotally mounted upon the frame of a vehicle; a vertically reciprocating shoe slidably mounted within the tubular member; means operatively connected to the shoe and adapted to lower the same into contact with a roadway; resilient

shock absorbing means interposed between the shoe and the operating means therefor; and a suitable rod operatively connected to the shoe and to the front end of the vehicle and adapted to prevent a backward movement of said shoe when the same is in contact with the roadway. 70

2. An antiskidding device for motor vehicles and the like comprising a vertically disposed tubular member pivotally mounted upon the frame of a vehicle; a sleeve slidably mounted within the tubular member and having the upper end thereof closed; a vertically reciprocating shoe slidably mounted within the sleeve; resilient shock absorbing means interposed between the top of the shoe and the closed top of the sleeve; and means operatively connected to the sleeve and adapted to lower the same and thereby bring the shoe into contact with a roadway. 75

3. An antiskidding device for motor vehicles and the like comprising a vertically disposed tubular member pivotally mounted upon the frame of a vehicle; a sleeve slidably mounted within the tubular member and having a closed upper end thereto; a shoe slidably mounted within the sleeve; a suitable spring interposed between the top of the shoe and the closed end of the sleeve; and a suitable lever pivotally mounted upon the vehicle and operatively connected to the sleeve whereby the same may be raised or lowered and the shoe brought into contact with a roadway. 90 95

4. An antiskidding device for motor vehicles and the like comprising a vertically disposed tubular member pivotally mounted upon the frame of a vehicle and having longitudinal slots in the sides thereof; suitable braces pivotally mounted upon the frame with the tubular member and adapted to brace the same laterally; a sleeve slidably mounted within the tubular member and having the upper end closed and lateral lugs thereon projecting through the slots in the tubular member; a shoe having longitudinal grooves on the lower surface thereof slidably mounted within the sleeve; a suitable spring interposed between the top of the shoe and the closed top of the sleeve; and a suitable lever pivotally mounted upon the frame and operatively connected to the sleeve whereby the same may be lowered and thereby bring the shoe into contact with a roadway. 100 105 110 115

5. An antiskidding device for motor vehicles and the like comprising a vertically disposed tubular member pivotally mounted upon the frame of a vehicle and having longitudinal slots in the sides thereof; suitable braces pivotally mounted upon the frame with the tubular member and adapted to brace the lower end of the member against lateral movement; a sleeve slidably mounted 120 125 130

within the tubular member and having the upper end thereof closed and lateral lugs thereon projecting through the slots in the tubular member; a shoe slidably mounted 5 within the sleeve and having longitudinal grooves in the bottom thereof adapted to engage a roadway and thereby prevent a lateral movement of a vehicle to which it is attached; a suitable spring interposed between the top of the shoe and the closed top 10 thereof; a suitable bracket secured to the

frame; a bell crank lever pivotally mounted upon the bracket and adapted to engage the lugs on the sleeve; and a suitable lever pivotally mounted upon the frame and operatively connected to the bell crank lever whereby the sleeve may be raised or lowered and the shoe slidably mounted therein may be brought into contact with a roadway. 15

In witness whereof I hereunto set my signature. 20

WILLIAM NORTON.
